UNITED STATES PATENT OFFICE.

EDWARD W. BUCH, OF BRIDGEPORT, CONNECTICUT.

DESIGN FOR A FENCE.

SPECIFICATION forming part of Design No. 26,809, dated March 23, 1897.

Application filed August 17, 1896. Serial No. 603,092. Term of patent 14 years.

To all whom it may concern:

Be it known that I, EDWARD W. BUCH, a citizen of the United States, residing at Bridgeport, in the county of Fairfield and State of Connecticut, have invented and produced a new and original Design for Fences, of which the following is a specification, reference being had to the accompanying drawing, forming a part thereof.

10 In the drawing the figure thereof represents a side elevation of a section of fence constructed according to my design.

The fence constructed according to my design is made up of a post 1, having a base 2, 15 a rectangular portion 3, containing the design of an oak-leaf on each face thereof, and a head-piece 4, made substantially circular in cross-section with scrolls or other ornamental designs thereon, the same constituting a pot 20 for containing flowers, ferns, and the like.

These fence-posts are arranged at regular intervals, and the head-pieces or flower-pots 4 are connected by two chains 5 6, arranged in loops one above the other, and the rectangular portions 3 are connected by an ornamental 25 rod or chain 7.

Having now described my invention, what I claim as new, and desire to secure by Letters Patent, is—

1. The design for a fence substantially as 30 herein shown and described.
2. In a design for a fence the post, substantially as herein shown and described.

In testimony whereof I have affixed my signature in the presence of two witnesses.

EDWARD W. BUCH.

Witnesses:

HENRY C. BARTLETT,
CHARLES RYDER.
